UNITED STATES PATENT OFFICE.

JOHN L. DUNNOCK, OF BALTIMORE, MARYLAND.

BOTTLE CLOSURE.

Application filed April 3, 1923. Serial No. 629,691.

To all whom it may concern:

Be it known that I, JOHN L. DUNNOCK, a citizen of the United States, residing at Baltimore city, State of Maryland, have invented certain new and useful Improvements in Bottle Closures, of which the following is a specification.

This invention relates to bottles designed primarily for use in connection with caps or closures such as shown, for example in Patent 1,169,938 issued to me on February 1st, 1916. These caps have spaced internal ribs between slits in the walls of the caps adapted to engage annular shoulders on the bottles to which the caps are applied. Some difficulty has been experienced in removing these caps from the bottles and an object of this invention is to so construct a bottle that, by rotating the cap on the bottle neck, the ribs on the cap will be pressed outwardly from under the annular shoulder engaged thereby. Thus the cap is released and can be removed readily from the bottle without the use of a tool.

With the foregoing and other objects in view which will appear as the description proceeds, the invention consists of certain novel details of construction which will be hereinafter more fully described and pointed out in the claims, it being understood that changes may be made without departing from the spirit of the invention as claimed.

In the accompanying drawing the preferred form of the invention has been shown.

In said drawings:

Figure 1 is an elevation of a bottle having the present improvements, a cap being shown in section thereon.

Figure 2 is a section on line 2—2, Figure 1.

Referring to the figures by characters of reference, 1 designates a bottle neck having

an annular groove 2 forming a shoulder 3. 45 The groove is intersected by deflecting cams 4 formed integral with the bottle neck, each cam being provided at one side with a radial shoulder 5 while its other side is substantially tangent to the inner wall of the 50 groove and constitutes a deflecting surface, as shown at 6.

The cap to be used with the bottle has been shown at 7 and has slits 8 arranged in pairs in the wall 9 thereof. The metal between the slits of each pair is offset inwardly to form ribs 10 and these are adapted to be snapped past the shoulder 3 into groove 2 at points between the cams. When it is desired to remove the cap it is merely 60 necessary to rotate the cap and bottle relative to each other so as to cause the deflecting faces 6 of the cams to press outwardly on the ribs 10. Thus the ribs will be pushed from engagement with the shoulder 3 and 65 the cap can be removed readily.

What is claimed is:

1. A bottle having an annular groove around the neck thereof forming a cap retaining shoulder, and deflecting cams integral with the bottle and intersecting the groove, said cams extending in the direction of the circumference of the neck and a portion of each cam being flush with the edge of the shoulder. 70

2. The combination with a bottle cap having an annular shoulder provided with inwardly projecting shoulder engaging ribs; of a bottle having an annular groove forming a shoulder beneath which said ribs engage, and cams in said groove extending in the direction of the circumference of the neck and each having a portion arranged to lift a respective rib to a level with the surface of the neck above the groove. 75 80 85

In testimony whereof I affix my signature.

JOHN L. DUNNOCK.
